UNITED STATES PATENT OFFICE.

CARL F. MEAD, OF CLEVELAND, OHIO.

WIRE-DRAWING MECHANISM.

Application filed March 26, 1925. Serial No. 18,495.

This improvement relates to wire drawing mechanism and is an improvement upon the invention shown, described and claimed in my Patent No. 1,682,393 of August 28, 1928, for wire drawing mechanism.

The object of the present invention is generally to provide improved readily releasable clamping or holding means for the free end of the wire, to improve the wire holding rods or hooks upon which the wire is collected after it leaves the drum, and to improve the mechanism for removing the finished coil from the drum.

Further objects of the invention are in part obvious and in part will appear more in detail hereinafter.

In the drawings, which represent one suitable embodiment of the invention, Fig. 1 is a side elevation; Fig. 2 is a plan view of the drum on a larger scale; Fig. 3 is a detail sectional elevation on the line 3—3, Fig. 2, and illustrating the coil removing mechanism; and Fig. 4 is a detail sectional elevation, on a larger scale, on the line 4—4, Fig. 2, and showing the operation of the wire holding rods or hooks.

The wire drawing mechanism shown in the drawings, generally speaking, is of the same construction and arrangement shown in my prior application referred to. It comprises the usual frame 1 in which is mounted a vertical spindle 2 driven through the gear 3, 4 from a power shaft 5. On said spindle 2 is a clutch member 6 adapted to drive a clutch member (not shown) on the drawing drum 7 when the latter is permitted to drop into driving relation with the clutch 6. As shown, the coupling of the drum driving clutch is controlled by a lever 8 pivoted at 9 in the frame and actuated by a manually operable bell crank lever 10, the lever 8 being provided with rollers 11 adapted when the lever 10 is moved in the counter-clockwise direction, Fig. 1, to elevate the drum and uncouple it from driving relation with spindle 2.

The wire is led to the drum through the usual die block mounted in a frame 12 pivoted at 13 on the stationary frame.

The drum shown in the drawings is of usual form in so far as it includes the cylindrical body portion 14 tapering slightly toward the top so that the wire will readily travel upwardly thereon and is provided at its bottom with a flange 15 over which the wire is coiled upon the drum. However,

upon the body portion is supported a conical or tapering top or upper member 16 provided with a spirally inclined track formed by the shoulder of a rib 17, said track leading upwardly in spiral form to a cylindrical or slightly tapered upper extension 18 of the cone 16, where the track terminates opposite one end of a transverse recess 19 in said extension. Here are provided the means for releasably gripping or holding the free end of the wire, to wit, a roughened or toothed plate 20 removably secured in one side wall of the recess and opposite which is located a laterally adjustable wedge member 21, that face of said wedge member nearest to the block 20 being parallel thereto and its opposite face being inclined, so that adjustment of the wedge transversely of the central axis toward its smaller end, as shown in Fig. 2, will clamp the wire end more or less firmly against the roughened block 20, while its adjustment in the opposite direction will release the wire. For convenience the wedge may be provided with an elongated slot 22 through which extends the holding bolt 23 and the wedge may be manipulated or adjusted in either direction by tapping or pressing upon its outwardly extending free ends.

Having so fastened the free end of the wire in the upper portion of the drum the latter is dropped into driving relation with the driving clutch 6 and the wire is coiled or laid alongside the track 17 in spiral form and then along the cylindrical portion of the drum until its bottom flange 15 is reached, whereupon, as in ordinary practice, successive turns of the wire are crowded in, one beneath another, after the manner of laying rope on a capstan, the finished coils being pushed upwardly along the drum body. The spiral arrangement, as in my prior application, progressively, positively and uniformly increases the speed of travel of wire through the die block from approximately zero to maximum speed and avoids excessive strain upon the wire during the starting operation, such as frequently causes breakage and interference with continuous operation.

It is the practice in wire drawing mechanisms of this class to permit the completed coils to rise along the drum and finally leave the upper edge of the cylindrical body thereon, one after another, such turns being collected upon rods or hooks extending upwardly from the drum body along the pe-

riphery thereof. In ordinary practice, these rods or hooks are set or placed in their openings by the workmen before the drawing operation is started, but obviously the addition to said drum of the conical upper portion with the spiral track thereon along which the wire is led downwardly according to my invention prohibits upward extension of said rods from the cylindrical drum body during the starting operation. As a result, in my patent referred to, I provided hooks or rods which during the starting operation lay below or did not extend above the lower end of the conical top of the drum and which rods were caused to rise with the wire as the finished coils thereof left the cylindrical body of the drum. According to the present invention I have so improved said rods or hooks as to materially increase their wire holding capacity, permitting effective upward rising or extension of said rods to a degree not heretofore obtained and thereby enabling larger coils to be completed with a single strand. In the present construction said hooks or rods are of telescoping or extensible form, including a tubular or hollow body portion 25 enlarged at the bottom to form a head 26 which travels within a vertical opening 27 in the boss of the drum body. The upper end of said opening is partly closed either by the metal around the edge of the hole in the overlying cone or, as shown, by the inwardly extending edges of a plate or flange 28 fitting fairly closely the body of the tube 25, so that throughout its vertical movement the body 25 is guided and held truly vertical at two points, to wit, at the head 26 where the latter slides along the wall 27 and at the plate or flange 28 along which the body of the tube 25 slides. The second member of the rod or hook is a bar 29 having the hooked upper end 30 and an enlarged head 31 travelling in the central opening of the member 25.

Several of these rods or hooks are spaced around the periphery of the drum, four in the instance shown. At the beginning of the drawing operation the upper member 29 is telescoped into the member 25 and said two members together are dropped to their lowest position in the recess 27, or to approximately the dotted line position, Fig. 4, with the hooks 30 extending radially outwardly, as in Fig. 2. Consequently, during the starting operation the wire travels from the clamp at the top of the cone downwardly along the conical track which terminates at the top of the cylindrical body of the drum between two of the rods or hooks, so that the wire passes upon the cylinder between two of said rods or hooks and then is laid spirally down to the flange 15. As successive coils are now laid upon the drum, each beneath the preceding one, the upper coils

finally rise to the hooks and engage the hooked upper ends thereof, and as successive coils leave the top of the cylinder they elevate the rods or hooks with them until finally said rods or hooks have been lifted to their extreme upper positions and confine or hold in proper position a large bundle of wire, represented generally by the dotted line A, Fig. 4. As successive coils leave the top of the cylinder and rise, the spiral portion of the wire lying along the rib 17 leaves said rib and rises with said coils, so that there is no binding or straining of the wire as the coil increases in height. The finished coil is ready to be removed from the drum when its initial end is unclamped from the cone.

The coil removing mechanism is shown more particularly in Fig 3. It is suspended from a crane or other overhead apparatus or support and includes a central rod or spindle 31 provided with a suspending eye 32 and at its lower end having a head 33 connected by a series, say 4, of radially extending links 34 to a like number of arms 35 pivoted at their upper ends to a spider frame 36, the hub 37 of which slides vertically on rod 31 and is adapted to be supported in its upper position by a gravity or other suitably operated hook 38 having an operating handle 39. The lower ends of the arms 35 are provided with hook portions 40. To properly engage the removing apparatus with the coil, provision is made for the entry of said arms into the cone and cylinder of the drum and their outward movement into coil engaging position. In the form shown, the drum, including the conical top 16 and the cylindrical body 14 is provided with four spaced radially extending slots 41, which intersect the rib 17, and into which the arms 35 are introduced by downward motion of the removing apparatus. In engaging the arms with the coil by downward motion the hook 38 is released from the hub 37 and the latter lies at its lowest position on rod 31, or adjacent the head 33. In said position the hooked ends 40 of arms 35 lie inwardly near the axis of the apparatus. As the mechanism is lowered the hooked ends 40 engage the upper inclined surfaces 42 of webs 42^a extending outwardly from the center of the drum cylinder beneath the slots 41, so that downward motion of the arms 35 and their supporting spider frame 36 is first prevented or continued lowering movement of the rod 31 and head 33 permits the links 34 to turn and the lower ends of the arm 35 to move outwardly and downwardly along the surfaces 42 until finally in the lowermost position of the mechanism the hooked ends 40 of said arms extend outwardly beneath the lower end of the formed coil. In this position the hook 38

38 has wiped over the upper flange of the hub 37 and has engaged beneath the same. Consequently if each of the wire holding hooks 30 is turned 180 degrees to free its hooked upper end from engagement with the top of the wire coil, said hooks drop and the lifting apparatus may be elevated by its crane and the wire coil carried up with it, it, of course, being understood that 10 the initial free end of the wire is first released or unclamped from the drawing drum. When the coil has been carried to its new position, handle 39 may be manipulated to release the frame 36 which with 15 the coil falls and causes the hooked ends 40 to move inwardly and release the coil, which is deposited in its proper place.

When the rods or hooks are seated in their lowest position in the drum, with the 20 hook ends turned outwardly they are held in proper position to be raised automatically by the growing coil. When in their upper positions, with hooks above the cone, the hooks may be readily turned by a manual operation so as to disengage them from the coil, but while they are being lifted by the growing coil the engagement of the wire therewith prevents the hooks from turning inwardly.

30 With this apparatus it is possible to wind a very large coil of wire with a progressively, positively and uniformly increased starting speed varying from zero to maximum speed and to properly pile up said coil 35 above the drum and confine it by the hooks described until it is removed by the lifting apparatus and is conveyed to its proper place.

In use of these winding drums the wire 40 drawn upon and rising along the drum frequently wears the drum surface so that the cylindrical portion of the drum must be renewed or replaced at intervals. To prolong the life of the cylindrical portion of the 45 drum I have provided the body thereof with a series, four being shown, of replaceable wear plates, marked 45. Neglecting the slight conical form of the drum, and assuming it to be a cylinder, each of said segments in shape is one-quarter of a cylinder 50 and is a wear resisting metal plate or facing, made of steel or the like, with its lower edge entering a recess in the base flange of the drum, as at 46, and provided, if desired, 55 with an inwardly extending upper flange 47 lying and held between the upper edge of the cylinder and the flange of the cone. These wear plates may also be secured in any suitable manner, such as by the threaded shanks 48 fastened through openings or 60 slots in the wall of the drum and upon which the clamping nuts 49 are threaded.

What I claim is:

1. A wire drawing drum provided with 65 substantially cylindrical and conical por-

tions, an axially extending portion provided with a transversely extending recess, and wedge means adjustable in said recess for securing the leading end of the wire therein, said wedge means extending outwardly beyond 70 said axially extending portion for manipulation at either end.

2. A wire drawing drum having a conical upper portion having an upper extension provided with a diametrically extending 75 recess, means for securing the wire in said recess, and a spiral wire guiding track extending downwardly along said conical portion from one end of said recess and along which the wire is led during the drawing 80 operation.

3. A wire drawing drum provided with a substantially cylindrical body portion and a wire starting conical portion above the same, in combination with extensible means 85 normally out of the path of the wire as it is laid upon the starting portion and so arranged as to rise above the cylindrical body portion a greater distance than the height of said body portion.

4. A wire drawing drum provided with a substantially cylindrical body portion and a wire starting conical portion above the same, in combination with extensible wire holding means adjustable vertically relative 95 to the drum and arranged to be lifted by the rising coil above the drum a greater distance than its own height.

5. A wire drawing drum provided at intervals around its periphery with wire 100 holding devices adjustable vertically relative to the drum and each including telescopically related members adapted for extension above the drum as the coils leave its upper edge.

6. A wire drawing drum, comprising a substantially cylindrical body portion, a conical portion above the same, a spiral track upon said conical portion, and coil lifting members cooperating with said drum and 110 expandable outwardly to engage the coil from its center, said conical portion being provided with openings interrupting said track, for the entry of said lifting members into the cylindrical body portion.

7. A wire drawing drum, comprising a substantially cylindrical body portion, a conical portion above the same, a spiral track upon said conical portion, coil lifting members cooperating with said drum and expandable outwardly to engage the coil from its center, said conical portion being provided with openings interrupting said track, for the entry of said lifting members into the cylindrical body portion, and means beneath 120 said conical portion for causing outward movement of said members.

8. A wire drawing drum, comprising a substantially cylindrical body portion, a conical portion above the same provided with 130

a spiral wire guiding track, and coil lifting members cooperating therewith and expandable outwardly to engage the coil from its center, said conical portion being provided with radially extending slots intersecting said track and adapted for the entry of said lifting members into the cylindrical body portion.

9. A wire drawing drum having a substantially cylindrical outer surface provided with removable wear resisting facing means, and a bottom flange provided with an annular channel in which said means is seated.

10. A wire drawing drum having a substantially cylindrical body portion, a plurality of removable wear resisting segmental plates on the cylindrical drum surface, said plates having flanges at their upper edges extending inwardly over a shoulder at the upper edge of the drum cylinder, and a conical wire starting member mounted on the drum with said plate flanges between it and the drum.

In testimony whereof I hereby affix my signature.

CARL F. MEAD.
